JOSEPH E. AIKEN, OF WILKINSBURG, PENNSYLVANIA, ASSIGNOR TO WESTINGHOUSE ELECTRIC & MANUFACTURING COMPANY, A CORPORATION OF PENNSYLVANIA.

SOUND-RECEPTION SYSTEM.

Application filed January 25, 1924. Serial No. 688,391.

My invention relates to apparatus for the translation of sound into vibratory electric currents.

Broadly speaking, the object of my invention is to construct a system for converting sound vibrations into vibratory electrical currents, which system shall respond to sound from a certain source more readily than to sounds from other sources.

10 More specifically, the object of my invention is to produce a sound-responsive device cooperating with sound-reflecting and sound-absorbing means which shall be adapted to be placed upon or near a rostrum at public exercises, and to be responsive to sound from a speaker at such public exercises and not responsive to extraneous sounds, such as applause, echoes and other disturbing noises, thereby giving a much more accurate copy 20 in vibratory electric currents of the sound waves produced by the speaker's voice.

In the development of the prior art of telephony, the microphones have, in great part, been of the type of the simple telephone transmitter suitable for the transmission of the voice of a speaker from a location close to the transmitter. Relatively few microphone devices have been suitable for the reception of speech when placed at a substantial distance from the speaker's voice. Because of the lack of such devices, the reception of sound from a speaker at a public exercise and its conversion into vibratory electric currents suitable for such purposes 30 as that of modulating the output of a radio sending apparatus, has been found difficult.

Because of this lack, the broadcasting of public speaking exercises by radio sending apparatus has been hampered and retarded 40 by the deficiencies of the response of available microphones. The microphone transmitters, which were developed for telephonic conversation, have relatively small mouth-pieces for the collection of the speaker's voice. They do not give adequate response to the speaker's voice when placed more than a few inches from his face. Therefore, when it was desired to translate the sound waves 45 of the speaker's voice into vibratory electric currents for the above purpose, difficulty was experienced by reason of the lack of sensitivity of the microphones. These must necessarily be placed at a substantial distance 50 from the speaker in order that the view of

the speaker from the audience might not be 55 obstructed.

Furthermore, when the sensitivity of an ordinary microphone was increased, or when sufficient amplification was applied to its output, it was found that the microphone responded not only to the speaker's voice but also to extraneous sounds of many kinds, including echoes and applause by the audience, to such an extent that the reproduction of the speaker's voice not infrequently was obscured and made entirely unintelligible.

My invention provides means for impressing a substantial amount of sound wave energy upon the microphone transmitter when the transmitter is at the desirable distance 70 from the speaker, and it further provides sound-absorbing means whereby undesired sound waves are restrained from influencing the microphone.

Other objects and structural details of my 75 invention will be apparent from the following description, when read in connection with the accompanying drawings, wherein:

Figure 1 is a view in elevation of my device in operative relation to associated objects, and

Fig. 2 is a plan view of the arrangement of Fig. 1.

Fig. 1 shows a rostrum 1, a speaker 2, a curved sound reflector 3 in combination with a microphone 4 to which is attached an outgoing electric circuit 5. The reflector 3 and the microphone 4 are preferably placed just behind the footlights 6, when footlights are present on the rostrum, or they may be hung from the ceiling, or otherwise disposed, in front of the speaker 2, with the axis of the reflector directed toward him. A sound-absorbent curtain 7 is placed behind the speaker 3. The reflector can guide to the microphone all the sounds which originate within a certain space, tapering toward the reflector, which is herein designated as the sound-reflective beam of the reflector. The curtain 7 is made sufficiently large in size to 100 cover the area, at its position, of the sound-reflective beam of reflector 3.

In describing the reception of sound by a microphone, it is convenient to distinguish between two types of sound. The sound emanating directly from the source, which it is desired to copy accurately into vibratory electric currents, may be called the primary

sound. The other sounds, such as echoes, applause and other extraneous noises, may be called secondary sounds. The purpose of my invention, then, is to obtain a maximum response of a microphone to primary sounds and a minimum response to secondary sounds.

In the operation of the device of my invention, the primary sound from the source 2 enters the opening of reflector 3, strikes its surface and is concentrated by reflection upon the sound-sensitive portion of microphone 4. In this way, an adequate amount of sound energy is impressed upon the microphone 4 from source 2, even though a substantial distance may intervene between them.

The increase in sound energy received by microphone 9, as compared to the energy received by an ordinary transmitter in the same position, is approximately in the ratio of the area of the front opening of the reflector 3 to the area of the front opening of the microphone with which it is compared. By this means, I am able to obtain sufficient response of the microphone when it is removed to a position where it will not interfere with the view of the audience, even though the distance from the speaker to this position be fairly great.

I also increase the ratio of response to primary sound, as compared to the response to secondary sound, by the reflecting powers of the reflector 3. The sound from the predetermined source enters the reflector 3, as shown, and is brought to a focus upon the transmitter 4. Sound striking the reflector from the opposite side is reflected away by the outer surface of reflector 3 and does not impinge upon the microphone 4, which lies in a sound shadow with respect to sound from the audience. This is indicated by lines 11, which are the path of travel of such a sound wave.

Other sounds which may originate upon the same rostrum, but in a position at one side of the speaker, may enter the reflector 3, as shown by lines 12, but such sounds are not brought to a focus upon the microphone 4 and, therefore, do not affect the microphone appreciably. Sounds originating in the audience may strike reflecting surfaces at the rear of the rostrum and thereby be reflected into the reflector 3 and be concentrated by it upon the microphone 4. To prevent this action, the curtain 7 is provided behind the speaker 2. This curtain is made of a sound-absorbent material and it damps out sounds striking it, thereby preventing the reflection of extraneous sounds into the reflector 7 from a direction which would allow it to concentrate those sounds upon the microphone 4.

Inasmuch as the sound-sensitive element of the microphone 4 has a finite size, the microphone is responsive to sounds which are brought to a focus over a definite portion of its area. The locus of points from which sound will be brought to a focus upon the finite area of the sound-sensitive element of the microphone by the mirror occupies the frustum of a cone whose small end enters the reflector. This cone is the boundary of the sound-reflective beam of the combination of the reflector 3 and the microphone 4. Sounds from any point in this cone will be received by the microphone, and, therefore, the source to which the microphone is desired to respond must be placed therein. Also, any sound reflected by a reflecting surface therein will affect the microphone. For this reason, the sound-absorbent curtain 7 is made of a size sufficient to cover the sound-reflective beam of reflector 3.

By means of this invention, I am able to secure an accentuated response of a microphone to predetermined sounds, thereby greatly increasing the ratio of such response to the response caused by other sounds.

My device is particularly adapted to the reception of, and response to, the sounds produced by a speaker at a public exercise, thereby producing an accurate copy of the speaker's voice, relatively unaffected by extraneous noises, by means of apparatus which is inconspicuous to the audience.

While I have shown only one embodiment of my invention in the accompanying drawings, it is capable of various changes and modifications without departing from the spirit thereof, and it is desired, therefore, that only such limitations shall be imposed thereon as are indicated in the prior art or in the appended claim.

I claim as my invention:

A sound-collecting system for use upon a rostrum to collect the sound of a speaker's voice but to shut out the sounds set up by an audience, comprising a reflector having a focus disposed between the audience and the speaker sufficiently spaced from the speaker to provide an unobstructed view of him and directed toward the speaker, a microphone at the focus of the reflector, and a loose fabric supported behind the speaker, said fabric being an efficient sound absorber and poor reflector, thereby reflecting no sounds from the audience upon the reflector.

In testimony whereof, I have hereunto subscribed my name this 21st day of January, 1924.

JOSEPH E. AIKEN.
